UNITED STATES PATENT OFFICE.

ELMER M. JONES, OF ATLANTA, GEORGIA, ASSIGNOR TO JONES SIGNAL SYSTEM COMPANY, OF ATLANTA, GEORGIA, A CORPORATION OF GEORGIA.

AUTOMATIC TRAIN-STOP OR CAB-SIGNAL.

1,290,223.

Specification of Letters Patent.

Patented Jan. 7, 1919.

Application filed September 13, 1915. Serial No. 50,289.

To all whom it may concern:

Be it known that I, ELMER M. JONES, a citizen of the United States, residing at Atlanta, in the county of Fulton and State of Georgia, have invented a certain new and useful Improvement in Automatic Train-Stops or Cab-Signals, of which the following is a full, clear, and exact description, reference being had to the accompanying 10 drawings.

This invention relates to automatic train stops, cab signals or similar indicators of the mechanical trip type, wherein a train or car is provided with a movable member, the 15 actuation of which may apply a brake, give a signal or otherwise control the train, and the trackway is provided with movable ramps or impingement devices located at intervals and adapted to be positioned in active 20 or idle position, according to the track conditions. My invention is concerned with both the vehicle device, which when actuated opens an air vent giving a signal or applying a brake, and with the track equipment, 25 which in this case is pneumatically operated and electrically controlled. My system is especially well adapted for use on such railroads (for example, elevated roads) as are provided with pneumatically operated and 30 electrically controlled track signals, and operates in harmony with such signals. With such initial equipment, I simply tap the air line for my operating power and the electric line for the controlling energy, without 35 interfering in any way with the present track signals. My invention is hereinafter more fully explained and its essential characteristics set out in the claims.

In the drawings, Figure 1 is a side elevation of a portion of a trackway and a car equipped with my automatic stop; Fig. 2 is a sectional side elevation and Fig. 3 is a sectional plan of the vehicle equipment; Figs. 4 and 5 are respectively a longitudinal section and an end view of the air valve seat; Figs. 6 and 7 are respectively a side elevation and an end view of the air valve plug; Fig. 8 is a plan, partly broken away, of the ground or track device; Fig. 9 is a 45 vertical section of the track device, being taken at right angles to the track rail and on a scale larger than Fig. 8; Fig. 10 is a diagram illustrating the connection of my system to the existing air and electric signal lines.

As shown in Figs. 1, 2 and 3, 10 is the casing of my vehicle equipment, which is a rectangular box-like frame adapted to be secured to the truck of a car or other vehicle. As shown in Fig. 1, the frame is secured to 60 the outer side of a longitudinal member A of a truck supporting a suitable car B. The wheels of the truck travel on the rails C supported on the ties D, which constitute the trackway.

The casing 10 for the vehicle equipment is shown as having a top plate 11, a rear or inner wall 12, end walls 13 and 14, inwardly extending bottom portions 15 and 16 near the opposite ends, and a low front wall 17. 70 Above the low wall 17 I provide a suitable cover plate 18 (Fig. 1), thus completing a box open only below.

Bolted to the upper wall of the casing 10 is the seat member 20 of the air valve. This 75 member is shown in detail in Figs. 4 and 5. It consists of a bracket having a central opening 21 threaded for the reception of an air pipe and terminating at its lower end in a partially cylindrical face 22. Extending 80 downwardly at opposite ends of this curved face are bifurcated legs 23 and 24. The bracket is shown secured to the upper plate of the casing by cap screws passing through openings 25 in the bracket. The other member of the air valve consists of a cylindrical barrel or plug 30 having the same curvature as the seat 22 and having gudgeons 31 at its ends occupying the bifurcations of the legs 23 and 24. Extending into a radial opening 85 in the under portion of the valve plug is a strut 35 which is shown as secured somewhat loosely to the barrel by a pin 36. The barrel and seat form a ground joint, and, when the barrel is pressed upwardly to the 95 seat by the strut, it seats snugly and the escape of air through the opening 21 is prevented. However, when the barrel is allowed to drop, the air pipe connected with a passageway 21 is thereby vented, which, as 100 is well understood, will apply brakes or operate a signal, as desired.

To maintain the plug 30 against its seat and allow it to drop when desired, I provide the following mechanism. Pivoted on a rod 40 (secured to the side members of the casing), is a lever 41 having a downwardly inclined portion 42 and an upwardly inclined portion 43 with an end projection 44 which overhangs the casing bottom 16. The bot- 110

tom 15 at the other end comes close to the pivot of the lever and the lever is substantially as wide as the space between the side plates 12 and 17, and thus forms a movable 5 bottom for the casing. Extending upwardly from the pivot 40 is an extension 45 of the lever, the upper end of which is pivotally connected to a bar 46. This bar is shown as extending diagonally downward 10 from its pivot, then horizontally at 47, then upwardly at 48 and finally having a horizontal extension 49. The extension 49 normally engages and is supported by the hooked end or catch 50 of an upright rod 51, which 15 is pressed upwardly by a surrounding spring 52. The spring and rod are mounted in a housing 53 bolted to the top plate 11, the spring resting at its lower end against the base plate of the housing and at its upper 20 end against a collar 55 on the rod.

The strut 35 which, as stated, is connected with the valve plug, is pivoted at its lower end between ears 57 on the under side of the portion 47 of the bar 46. The lever 41 is 25 normally held in the position shown in Fig. 2, by means of the compression spring 60, which is shown as located in a tube 61 pivoted to the casing at 62, the spring surrounding a rod 63 and bearing against a collar 64 thereon. The rod extends out of the casing, as shown at 65, where it is pivoted to a bracket 66 secured to the upper face of the lever 41.

The spring 60 holding the lever 41 in the 30 position shown, the left hand end (Fig. 2) of the bar 46 is held elevated, and the right hand end being held up by the catch 50, the barrel 30 is maintained against its seat under pressure of the spring 52. This 35 spring is strong enough to overcome the air pressure on the barrel through the opening 21, so that the valve remains closed. Now, it will be seen that the upward movement of the lever 41 will move the pivot of the 40 bar 46 to the left (Fig. 2), and withdraw the nose 49 from the catch 50, whereupon the bar 46, the strut 35 and the barrel 30 will drop by gravity, assisted by the air pressure in the pipe 21, which is thus opened.

45 The correspondingly numbered dotted lines in Fig. 2 show the position of the parts at the time when the air pipe is vented. Accordingly, to automatically apply the brake I provide an impingement member or ramp 50 along the trackway, which may be moved into a position so that the lever 41 engages it. When the forward movement of the car causes the lever to ride upwardly on the ramp, this shifts the bar 46 and releases the 55 air valve. After the lever 41 has cleared the ramp it drops by gravity to normal position, but when it returns the valve remains open as the bar 46 simply rides on the stationary stop 70 and comes into a position 60 where its left hand end is elevated and its

right hand portion depressed, the right hand portion being indicated at 49^a in Fig. 2.

To restore the bar 46 to normal position and thus close the valve, it is necessary to elevate the right hand end of it, and I do this by forcing downwardly the bar 51 against the action of the spring 52 until the inclined lower end or catch thereof slides over the end 49^a of the bar, whereupon the return of the rod 51 to elevated position under the influence of the spring 52 returns the bar 46 to normal position and closes the valve. This closing movement rocks the valve plug on its seat, thus insuring a clean and tight joint.

Any suitable means may be provided for depressing the bar 51. It is desirable, however, to provide means which are operable from the cab or some portion of the vehicle, and, as the vehicle mechanism described is 85 preferably mounted on the truck, there should be some flexible operating connection which would allow the turning of the truck on its king pin. Such flexible connection is indicated in Fig. 1, where 75 designates a 90 chain leading from the motorman's cab of the vehicle B to a bell crank 76 pivoted to the truck and connected with the bar 51. The chain may be pulled by hand, by an air device, or in any other manner.

95 I will now describe the track device which is adapted to be positioned to cooperate with the lever 41. This track device is pneumatically operated and electrically controlled. Its air supply is adapted to be received from 100 an air pipe along the trackway by means of a branch pipe having a T-connection with the track pipe. A suitable master valve in this track pipe is controlled by a magnet or solenoid energized by an electric circuit. 105 This master valve may be the controller for the track signal or may be additional thereto.

The diagram (Fig. 10) shows at 100 the main track air pipe, at 101 the branch pipe leading therefrom to an individual ground 110 device, and at 102 a master valve controlling the admission of air to the branch pipe. A pipe 103 is indicated as leading from the pipe 101 to a track signal. The master valve is adapted to be opened by a solenoid 105 115 which is energized by current coming over the lines 106 and 107, which may be the main signal lines or tapped onto signal lines 108 and 109. A suitable spring 110 is shown as tending to close the master valve.

120 The operation of this portion of the apparatus, which may be of any suitable form, is to normally admit air to the pipe 101, (when the solenoid is energized) but to vent that pipe whenever it is desired to throw the 125 ramp to active or stopping position. 104 indicates an air vent and 110 the spring tending to turn the valve barrel to vented position, when the solenoid is deenergized, this being the position shown in the diagram.

The ramp is illustrated in Figs. 1, 8 and 9 and is designated 120. It is shown as having a double-inclined top to present a peak. When this peak is below the level of the rail top, as shown in full lines in Fig. 9, the ramp is in clear position and the lever 41 of the vehicle device may pass idly over it. When the ramp is elevated into the position shown in dotted lines in Fig. 9 and in full lines in Fig. 1, it is in its active or danger position and operates to elevate the lever 41 and apply the brake or give a cab signal. The ground devices operates, as will now be explained, to elevate the ramp whenever the 15 air pressure or electric current fails, intentionally or accidentally.

The ground or track device is shown in Figs. 1, 8, 9 and 10. It is contained within a casing 125 located between ties and extending 20 outwardly beneath the rail and on the outer side of the rail, and is provided with upwardly extending parts 126 and 127 (Fig. 9) which form a bearing and guide for a plate 130, which forms the shank of the 25 double faced ramp 120. This ramp, in safety position, stands with its peak a slight distance below the top of the plane of the rail C. It is raised to danger position by an upward movement of the shank 130 30 which carries the peak to the position shown in dotted lines in Fig. 9 and in full lines in Fig. 1.

The shank of the ramp 130 is shown as guided near its lower portion by a pair of stationary cross rods 132 and 133. Extending into an opening in the shank above these rods is a lever 135 which is pivoted on a cross bar 136 and is heavily counterweighted on the opposite side of the lever, as indicated by the flaring extension 137. The 40 gravity, therefore, tends to swing the left hand end of this lever downwardly (Fig. 9) and thus raise the ramp.

In Fig. 9, 140 indicates a stationary piston mounted on the upper end of a pedestal 141 secured to the bottom of the casing 125. Surrounding this piston is a cylinder 143 having a flange 144 extending beneath the piston and carrying on its underhanging 50 portion the piston 146. Extending axially through the piston and pedestal is an air passageway 147, and when air is forced through this passage way it raises the cylinder 143.

On the upper end of the cylinder 143, is a pawl 150 which is adapted to coact with a pivoted latch 151 carried on the counterweighted lever and thus retain the lever in its elevated position, holding the ramp in 60 its lower or clear position. The latch 151 is connected by a link 152 with a bell crank 153, to which is connected a latch arm 154 slidably resting on a projection 155 of the lever arm 137. This latch arm coacts with 65 the pivoted latch 156 which carries or forms

the armature for a magnet 158. This magnet may be in series with the master solenoid 105 (as indicated in the diagram, Fig. 10). When energized, it holds the armature in the position shown in Fig. 9, and the linkage system remains as there shown with the catch 151 in position to be supported by the pawl 150. When, however, the magnet 158 is deenergized, the armature drops, and this releases the arm 154, thus releasing the catch 70 151, whereupon the counterweighted lever is no longer effectively engaged to the supporting pawl 150, and the lever drops by gravity until the extension 160 thereof strikes on the abutment bumper 161 (preferably a fiber block), on the upper end of the cylinder. Such movement raises the ramp sufficiently for it to be in danger position. In this falling movement the air in the cylinder forms a buffer, breaking the 80 shock.

It will be seen from the above that any failure in the electric current to the magnet 158, whether intentionally or from a broken circuit, or run-down batteries, will throw 90 the ramp to danger position. Any failure in the air supply to the cylinder, whether intentionally or accidental, will allow the cylinder to drop, carrying down the supporting pawl 150 and thus lowering the 95 lever, also raising the ramp to danger position. In the intended operation of the device to danger position the magnet 158 is deenergized and the air supply is also shut off to the cylinder.

When the counterweighted lever falls to the fiber block 161 it delivers a decided blow to the ramp shank, by reason of occupying a loose slot in the shank. This blow will break the ramp loose from any incasing ice 105 which might form on it, and it also raises it to a sufficient height to engage the car lever whether the cylinder falls or not. Therefore, if the cylinder should become frozen or otherwise prevented from lowering, the device nevertheless goes to danger position, which serves to immediately call the trainmen's attention to this condition.

When the counterweighted lever drops by reason of the magnet 158 being deenergized, 110 a bar 170 connected with the lever is shoved downward and a shoulder 171 thereon engages a pawl 172 on the end of an arm 173 which is connected with the shaft of an oscillatory air valve 174. This valve is located in a casing 175 interposed between the branch air line 101 and a conduit 176 leading to the passageway 147. Ordinarily the line is open from the pipe 101 to the pipe 176 by reason of the arcural recess 178 in 120 the oscillatory head 174. As the strut 170 shoves downwardly on the pawl 172 it swings this oscillatory head in the left hand direction (Fig. 9), against the influence of a spring 179 to close the pipe 101 and open 130

an exhaust pipe 180 communicating with the atmosphere in the casing 175. This frees the air in the cylinder 143 and the latter drops by gravity, thus allowing the counter-weighted arm to descend farther, until stopped by striking and resting on the cross-rod 182. This elevates the ramp to its highest position, as shown in dotted lines in Fig. 9.

10 The counterweighted arm follows downwardly, as stated, with the fall of the cylinder 143. As these parts reach their lowest position the cylinder impinges on a horizontal arm 185 of a bell crank pivoted on the 15 base of the pedestal 141 and having an arm 186 connected at its upper end with a slot 188 on the link 170. The weight of the cylinder depresses the horizontal arm 185 and thereby swings the link to the left (Fig. 20 9), which releases the pawl 172, and thereupon the spring 175 restores the valve 174 to the position shown in Fig. 9. In this 25 position, if air is supplied through the pipe 101 the cylinder is again raised, and, in rising, restores the counterweighted arm to the clear position shown in Fig. 9.

The valve 174, just described, is for the purpose of insuring a restoration of the air cylinder to elevated position, following the 30 actuation of the latch magnet 158, whenever the air is supplied through the master valve, such supply corresponding to a safety condition of the circuit controlling the master solenoid.

35 The air supply to the pipe 101 is, as stated, controlled by the master valve 102. This valve is shown as being simply an oscillatory cock, which, in the deenergized position of the solenoid, opens the pipe 101, 40 and, in the energized position, closes communication from the main pipe 100 and connects the pipe 101 with the vent 104. Accordingly, the energization of the solenoid 105 normally vents the cylinder 143, and, 45 under proper working conditions this is sufficient to throw the ramp to danger position.

In case, however, for any reason, the master valve should fail to vent when the solenoid is deenergized, the simultaneous 50 energizing of the magnet 158 (which may be in series with the solenoid), releases the catch 151, causing the counterweighted lever to drop, and putting the ramp in danger position. As stated, this movement is automatically 55 followed by the dropping of the cylinder and placing the parts in such position that, when the current is again established through the solenoid and magnet 158 the lever and ramp will be restored to 60 clear position.

Air used in electro-pneumatic signaling is usually dried before it is allowed to enter the service pipes, but, as an extra precaution water traps may be placed in the pipe 65 line leading to the stop machines, as indi-

cated at 191 in Fig. 10. To prevent any moisture which might get into the cylinder from possibly forming an ice coating across the upper end of the passageway 147, I provide a central boss 194 on the upper end of 70 the piston, thus leaving an outside annular channel for the precipitated moisture.

Having thus described my invention, what I claim is:

1. The combination with a movable track 75 member, of a pneumatic device and an electro-magnetic device acting conjointly to move the track member to clear position, and constantly acting means tending to move it to danger position, whereby the failure of either the electric supply or the air supply gives the track device a danger position.

2. The combination of a movable track ramp, a counterweighted lever tending to 85 move the same to danger position, and combined pneumatic and electric devices acting conjointly to sustain the counterweighted lever with the ramp in clear position.

3. The combination of a movable track 90 ramp, a counterweighted lever tending to move the same to danger position, an electro-magnetic latch carried by said lever, and a pneumatic operating device coacting with 95 said latch to raise the counterweighted end of the lever.

4. The combination of a movable track device, a counterweighted lever adapted to move said device, a latch carried by said lever, an electro-magnet for controlling said 100 latch, and a pneumatic motor having a movable member adapted to coact with said latch.

5. The combination with a stationary piston, of an upright cylinder embracing the 105 same, means for admitting fluid into the space between the piston and cylinder, a counterweighted track device, and mechanism for positioning it, including an electro-magnetic latch connecting it with the 110 cylinder.

6. The combination with a stationary piston, of an upright cylinder embracing the same, means for admitting fluid into the space between the piston and cylinder, a 115 track device, mechanism for positioning it including a counterweighted member adapted to descend by gravity, and an electrically controlled latch carried by said member and coacting with the cylinder.

7. The combination with a movable track ramp, of a counterweighted lever adapted to move the ramp, a stationary piston, an upright cylinder embracing the piston, means for admitting fluid into the cylinder 125 above the piston to raise the cylinder, and an electrically controlled latch between the cylinder and lever.

8. The combination of a track ramp adapted to be raised into danger position or de- 130

pressed into clear position, a counterweighted lever for so moving the ramp, a latch carried by the lever, electro-magnetic means for controlling the latch, a stationary piston, an upright movable cylinder surrounding the piston, and means carried by the cylinder co-acting with the latch.

9. The combination of a track device adapted to coact with indication mechanism on a vehicle, mechanism for moving the track device, pneumatic and electro-magnetic means acting conjointly for controlling said mechanism, and means whereby the failure of the electric current automatically releases the air in the pneumatic device.

10. The combination of a movable track ramp, counterweighted mechanism tending to move it to danger position when said mechanism drops, a pneumatic motor to raise said mechanism, an electro-magnetic latch adapted to release said mechanism, and means whereby the electro-magnetic release of the mechanism is automatically followed by the release of the air in the pneumatic motor.

11. The combination with an indication device on a vehicle, of a movable track device adapted to coact therewith, a pneumatic motor for moving the track device to clear position, a weight for moving it to danger position, electro-magnetic means for releasing the air in said motor, and means for automatically closing said release when the motor reaches the end of its stroke.

12. The combination of a movable track ramp, a pneumatic motor adapted to move the same to clear position, an electro-magnetic latch adapted to release the ramp, a weight adapted to move the ramp when released, mechanism operated by the falling weight to release the air from the motor, and means for automatically closing said release after the motor has moved into position corresponding to the danger position of the ramp.

13. The combination of a movable track ramp, a counterweighted lever tending to move the ramp into danger position, a pneumatic motor, and an electro-magnetic latch coacting and adapted to raise the counterweighted end of the lever, mechanism whereby the dropping of the lever or failure of the electric current releases the air in the mo-

tor, and mechanism for automatically closing such release at the end of the stroke of the motor.

14. The combination with vehicle indication mechanism, of a movable track device adapted to coact therewith, constantly acting means tending to move the track device to danger position, a fluid motor adapted to move the device to clear position, an electro-magnetically controlled valve for releasing the fluid in the motor, means for automatically closing such release after the motor is operated, and electrically controlled means for supplying pressure fluid to the motor.

15. The combination of a movable track ramp, a counterweighted lever adapted to move the same to danger position, a fluid motor and an electro-magnetic latch acting conjointly to raise the counterweighted lever, the failure of the electric current or the pressure fluid causing the lever to drop, means whereby the dropping of the lever automatically releases the fluid to the motor, means whereby such release is closed after the motor has moved, and means for controlling the air supply to the motor.

16. The combination of a movable track ramp, a counterweighted lever connected therewith, a stationary piston, a movable upright cylinder embracing the same, an electro-magnetic latch between the cylinder and lever, an automatic valve controlling the air supply to the cylinder and adapted to release such supply when the lever drops, and a controlling valve for controlling the supply of air to the automatic valve mentioned.

17. The combination of a movable track ramp, a counterweighted lever connected therewith, a stationary piston, a movable upright cylinder embracing the same, an electro-magnetic latch between the cylinder and lever, an automatic valve controlling the air supply to the cylinder and adapted to release such supply when the lever drops, means for restoring said valve to normal position when the released motor reaches the end of its effective stroke, and a controlling valve controlling the supply of air to the automatic valve.

In testimony whereof, I hereunto affix my signature.

ELMER M. JONES.
